Primary Examiner — Michelle E. Wilson*Assistant Examiner* — Caitlin A Laverty*(74) Attorney, Agent, or Firm* — Kristin D. Wheeler(57) **CLAIM**

The ornamental design for a golf bag as shown and described.

DESCRIPTION

FIG. 1 is a perspective view of a golf bag showing my new design;

FIG. 2 is a front view of a golf bag, thereof;

FIG. 3 is a back view of a golf bag, thereof;

FIG. 4 is a first side view of a golf bag, thereof;

FIG. 5 is a second side view of a golf bag, thereof;

FIG. 6 is a top plan view of a golf bag, thereof; and,

FIG. 7 is a bottom plan view of a golf bag, thereof.

In FIGS. 1-7, the lighter broken lines showing portions of the golf bag are for purposes of illustrating environment and form no part of the claimed design.
